US0D1066265S

(12) **United States Design Patent** (10) Patent No.: **US D1,066,265 S**
(45) Date of Patent: ** Mar. 11, 2025

(54) **CONTACTLESS SWITCH**

(71) Applicant: **OPTEX CO., LTD.**, Shiga (JP)

(72) Inventors: **Koki Horiguchi**, Shiga (JP); **Tomoyuki Ohba**, Tokyo (JP); **Chihiro Maruyama**, Tokyo (JP)

(73) Assignee: **OPTEX CO., LTD.**, Shiga (JP)

(**) Term: **15 Years**

(21) Appl. No.: **29/913,875**

(22) Filed: **Oct. 10, 2023**

(51) LOC (15) Cl. **13-03**

(52) U.S. Cl. USPC **D13/158**

(58) **Field of Classification Search**

USPC ..... D13/169, 171, 170, 162, 164, 184, 199, D13/182, 158, 173, 174, 177, 168 CPC .. H01H 3/12; H01H 9/16; H01H 9/18; H01H 9/1181; H01H 9/182; H01H 2009/187; H05B 33/0803; H05B 33/0863; H05B 39/02; H05B 39/04; H05B 39/085; H05B 39/086; H05B 39/088

(57) **CLAIM**

The ornamental design for a contactless switch as shown and described.

DESCRIPTION

FIG. 1 is a first perspective view of a contactless switch showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the figures are included for the purpose of illustrating portions of the contactless switch that form no part of the claimed design.

1 Claim, 6 Drawing Sheets
